UNITED STATES PATENT OFFICE.

FRITZ WEVER, OF STUTTGART, GERMANY.

SEWING-MACHINE.

No. 902,353.

Specification of Letters Patent.

Patented Oct. 27, 1908.

Application filed January 19, 1905. Serial No. 241,792.

To all whom it may concern:

Be it known that I, FRITZ WEVER, a citizen of the German Empire, residing at Stuttgart, in the Kingdom of Würtemberg, Germany, have invented certain new and useful improvements in Sewing-Machines, of which the following is a description, reference being had to the accompanying drawing, and to the letters and figures of reference 10 marked thereon.

My invention relates to attachments for sewing machines, whereby said machine is adapted for necking underwear. That is, the knit blank from which the shirt is to 15 be made, is cut in a predetermined outline, and one of said cut edges stitched to the body piece.

My invention consists in an attachment whereby the material is so held and manipulated that a circular portion is cut from the body fabric, and the edge of said circular portion stitched to the body fabric by a blind stitch.

My invention consists further in details 25 of construction which will be hereinafter set forth in the description and pointed out in the claims.

In the drawings: Figure 1 is a front elevation of a fragmentary portion of the 30 machine head with my attachment secured thereto, the certain parts being shown sectioned; Fig. 2 is a detail view of my attachment, parts being shown as sectioned; Fig. 3 is a detail view showing the back guide 35 and the clamping member coöperating therewith in separated position, and the fabric folded over said back guide. Fig. 4 is a plan view of the clamping jaws, together with the presser foot, needle and trimmers; Fig. 40 5 is a view of a shirt blank, as stitched on my machine, the stitches being indicated in this view merely by a dotted line; and Fig. 6 shows the manner of folding the shirt blank and the process of stitching partially 45 completed.

The parts of the sewing machine proper have been shown only in a fragmentary manner, as the machine is of the usual construction familiar to those skilled in the art 50 to which the invention relates. 30 is the needle, which is supported by the usual needle bar, and has coöperating therewith the usual complementary stitch-forming mechanism, which operates to form an overedge

stitch. 34 is the usual presser foot having 55 a shield or guide 31. 33 is the usual feed dog, coöperating with the presser foot to feed the material through the machine. 35 is the upper trimming member, and 32 is the lower trimming member. These parts are 60 all of the usual construction, and will not be further described in detail.

My invention relates to an attachment for a machine of the above characteristics. Secured to the machine frame by suitable 65 screws is a bracket 1, which has pivoted at its upper end a lever 3 by means of a pivot 2. The lever 3 supports my work holding attachment. The lever extends downward, substantially parallel with the needle bar, 70 for a short distance, and is then deflected outward away from said needle bar. At the lower end of the lever 3 is a bearing 10. A bearing 9 spaced from the bearing 10, but in alignment therewith is also carried by 75 said lever. Mounted in said bearing 9, and projecting through said bearing 10 is a shaft 4. Said shaft carries at its lower end a jaw 14. Said jaw consists of a plate arranged substantially at right angles to the 80 shaft 4 and secured thereto by a suitable screw. The outer edge of the jaw is bent at 85 15, so as to lie substantially parallel to the bed plate when adjacent the needle, and in position to hold the material for the needle 90 to penetrate the same. The portion 15 extends beneath the presser foot, as shown in Fig. 1, so that the material when bent over said edge will be held in such a position relative to the needle that said needle will 95 enter and emerge from the material on the same face, without penetrating entirely through the material to the other face, and thus forming a blind stitch. The edge of the jaw 15 which supports the back face of 100 the material, I term a back guide. This back guide as the material is fed, turns about the shaft 4 as an axis. The shaft 4 is capable of limited movement in the bearings 9 and 10, and is held in its elevated position 105 by a spring 11, bearing against the bearing 9, and against the collar 12, on the end of the shaft. When the presser foot is lowered, it engages the back guide 15, and moves the same with the shaft 4 against the tendency of the spring 11, until the material is firmly clamped against the bed plate 110 of the machine. This movement of the

parts adjusts the same for different thicknesses of material operated upon.

Surrounding the shaft 4, and engaging within the bearing 10 is a sleeve 6, which is slotted at 5; and receives a pin carried by the shaft 4, so that said sleeve 6 may move longitudinally of the shaft, but partakes of the axial movements of said shaft.

A spring 7 encircles the shaft 4, and bears 10 at one end on the sleeve 6, and at its other on a collar 8, secured to the shaft. The normal action of the spring 7 is to force the sleeve 6 toward the jaw 14. Rigidly carried by the sleeve 6 is a jaw 13, corresponding in outline to the jaw 14. By the action of the spring, the jaws 13 and 14 are kept in contact. An arm 21 is provided with ears 19 at its lower end, which are pivoted to a lug projecting from the bracket 1, so 20 that said arm has a horizontal movement. Extending along the upper edge of the arm is a cam ledge which engages the collar 6. The arm 21 is held in operative relation to the collar 6 by a flat spring shown in dotted 25 lines in Fig. 1. When the lever 3 is swung outward about its pivot 2, said cam operates to lift the jaw 13 against the action of the spring 7. Projecting from the bracket 1 are two arms 16-16, between which the lever 3 30 is guided in its movements.

The spring pin 17 (see Fig. 2) operates to hold the lever in its adjusted position. A screw 20 is carried by the lever 3 and bears against the bracket 1. By adjusting the 35 screw, the inward movement of the lever 3 is controlled and the position of the back guide relative to the needle determined. For thin goods, it is necessary that the back guide be brought closer to the needle, otherwise, the needle would miss entirely the material bent around the guide.

In order to insert the material, the lever 3 is moved to its outer position. By this movement the cam 18 engages the sleeve 6, 45 and separates the jaws. The goods are folded as shown in Figs. 3 and 6, and placed over the jaw 14. The lever is then swung to its inner position and the jaw 13, through the action of the spring 7 descends upon 50 the fold of the material, securely clamping the same to the lower jaw 14. As the feed of the goods takes place, the back guide is turned about the shaft 4 as an axis, and the material is therefore cut and stitched 55 in the circular outline shown in Fig. 6.

Having thus described my invention, what I claim as new and desire to secure by Letters Patent, is:—

1. The combination with stitch forming 60 mechanism, of a back guide over which the material is folded, and a clamping member coöperating with said back guide and moving therewith, means for supporting said back guide from the head of the machine, 65 whereby the body of the material folded

over said back guide, may pass underneath said guide, and means for moving the same in a circular direction.

2. The combination with stitch forming mechanism, a back guide over which the material is folded, whereby the needle may enter and emerge from the same surface of the material, means for clamping the material to said back guide, means for supporting said back guide from the head of the machine, and means for moving said back guide in a circular direction.

3. In a sewing machine having an overhanging arm, the combination with stitch-forming mechanism, of a back guide over 80 which the material is folded, means for supporting said back guide from the head of the machine means for clamping the material to said back guide, means for adjusting said guide relative to the needle, and means for 85 moving said back guide in a circular direction; substantially as described.

4. In a sewing machine having an overhanging arm, the combination with stitch-forming mechanism, of a back guide over 90 which the material is folded, means for supporting said back guide from the head of the machine means for yieldingly supporting said back guide, and means for moving said back guide in a circular direction and 95 a clamping member coöperating with said back guide; substantially as described.

5. The combination with stitch-forming mechanism, a work support of a guide over which the material is folded, means for 100 clamping the material to said back guide, means for yieldingly supporting said back guide above the work support whereby the body material may be passed underneath said guide and folded over on the same, and means for moving the same in a circular direction; substantially as described.

6. The combination of stitch-forming mechanism, a back guide over which the material is folded, means for yieldingly supporting said back guide from the head of the machine, whereby it may yield vertically, and means for adjusting the horizontal position of the back guide relative to the needle whereby the needle may be caused to 110 enter more or less into the folded portion of the material; substantially as described.

7. The combination of stitch-forming mechanism, a back guide, means for supporting the same, whereby it may yield vertically, means for adjusting the horizontal position of the back guide relative to the needle, and means for moving said back guide in a circular direction and a clamping member coöperating with said back guide 120 and moving therewith; substantially as described.

8. The combination of stitch-forming mechanism, a back guide, means for clamping the material to said back guide, means for 130

- for supporting said back guide, whereby it may yield vertically, and means for adjusting the horizontal position of the back guide relative to the needle; substantially as described.
9. The combination of stitch-forming mechanism, a back guide, means for clamping the material to said back guide, means for supporting said back guide, whereby it may yield vertically, means for adjusting the horizontal position of the back guide relative to the needle, and means for moving said back guide in a circular direction; substantially as described.
10. The combination of stitch-forming mechanism, a back guide comprising clamping jaws, means for yieldingly supporting said jaws, means for moving said jaws about an axis, means for moving one jaw relative to the other and means whereby said jaws may be bodily moved away from the stitch-forming mechanism; substantially as described.
11. The combination of stitch-forming mechanism, a back guide comprising clamp-
- ing jaws, means for supporting said jaws, means for moving said jaws about an axis, means whereby said jaws may be bodily moved away from the stitch-forming mechanism, and means for separating and closing 30 said jaws as they move away from and toward the stitch-forming mechanism; substantially as described.
12. The combination with stitch forming mechanism of a work support, a trimmer, a 35 movable back guide, means for supporting said back guide above the work support, whereby a plurality of layers of material may be placed thereon, with one layer folded underneath said back guide and the other 40 layer extending beyond said back guide into the path of the trimmer, and means for clamping said layers of material to the back guide.
- In testimony whereof I affix my signature, 45 in presence of two witnesses.
